UNITED STATES PATENT OFFICE

ADOLPH POTDEVIN, OF GARDEN CITY, NEW YORK, ASSIGNOR TO POTDEVIN MACHINE COMPANY, OF BROOKLYN, NEW YORK, A CORPORATION OF NEW YORK

BAG MACHINE

Application filed March 3, 1928. Serial No. 258,876.

My invention relates to an improvement in machines for making paper bags. In such machines the material from which the bags are to be manufactured is fed customarily 5 into one end of the machine, where paste is applied to the edges of the paper, the paper then being folded over and the over-lapping edges pressed together to form a seam. This provides a tubular formation which is next 10 cut to length, depending, of course, upon the type of bag being made. The tube next passes to bottoming mechanism where the bottom is formed. The machines are full automatic in operation.

15 It has been found, however, in the manufacture of bags on such machines that occasionally the seams will open during manipulation of the tubes in the bottoming operation, which unfits the bags for service where 20 bagging of finely divided material is desired, and the machines being automatic in operation this may not be discovered until a great number of bags have been run through.

One of the objects of my invention, there- 25 fore, is the provision of a bag machine in which means are provided whereby the tubes are so treated after leaving the tube-forming mechanism and before reaching the bottoming mechanism that opening of the seams 30 during the bottoming operation is avoided.

In general, my invention provides means intermediate the tube-forming mechanism and the bottoming mechanism for passing or transferring the tubes from the tube-forming 35 mechanism to the bottoming mechanism, the seams of the tubes during such transfer being subjected to pressure by the transferring mechanism and the paste in the seams allowed to dry and set sufficiently to prevent possi- 40 bility of the seams opening during the bottoming operation.

In the accompanying drawings Fig. 1 is a part sectional elevational view of my invention;

45 Fig. 2 is a plan view of the apparatus of Fig. 1;

Fig. 3 is a detail view of certain mechanism employed adjacent the bottoming end of the machine;

50 Fig. 4 is a detail view showing one stage of

the passage of the tubes through the apparatus; while

Fig. 5 is a view in perspective of a tube of paper prior to the bottoming operation showing the manner in which the seam may open 55 during the bottoming operation, a defect which, as above pointed out, is remedied by the present invention.

Referring now to the drawings in detail, the paper or other material from which the bags are to be made is fed from a roll into the machine, pasted, and folded over so that the edges overlap to form a seam extending longitudinally of the tube. Inasmuch as the mechanism necessary to the performance of this much of the bag forming operation is well known in this art the same has not been illustrated and will not be referred to in detail. The material in tube form is next passed through cutting off mechanism, shown 60 more or less diagrammatically at 2 in the accompanying drawings, where the tube is cut off to the desired length.

It may be well to mention at this point that the tubes may be made with a center seam or 65 with a side seam, as the case may be, the apparatus constituting the present invention being adapted for use in the making of both types of bag.

Beyond the cutting off mechanism a pair 70 of positively driven discharge or delivery rolls 3 and 4 are provided, the tubes after being cut to length passing between these rolls and being discharged thereby successively upon the upper lead of a positively 75 driven conveyer belt 5, which constitutes a part of my improved mechanism. The conveyer belt is endless and is mounted on a series of rollers 6, 7, 8, 9, 10 and 11, the rollers 10 and 11 being so disposed relatively to each 80 other that the direction of travel of the conveyer belt with respect to the direction of travel of that portion of the belt lying between the rollers 6 and 11 is reversed.

The paper tubes as they are discharged by 85 the rolls 3 and 4 are deflected by members 14 so as to be deposited properly upon the conveyer belt. 12 designates tubes which have been deposited upon the belt, while 13 designates a tube being discharged from the 90 95 100

rollers 3 and 4. The tubes have been illustrated as lying upon the belt in overlapping relation, and this relation is obtained by properly regulating the speed of the belt with relation to the rate at which the tubes are discharged by the rolls 3 and 4. Obviously, if desired, the length of overlap may be varied or the tubes could be deposited upon the belt so as not to overlap at all, by simply speeding up the rate of travel of the conveyer belt 10 with reference to delivery speed of the rollers 3 and 4. However, the overlapping relation of the tubes may be preferable in many instances, inasmuch as the slower the conveyer belt is caused to travel relatively to the 15 delivery of the tubes by the rolls 3 and 4, the more time will elapse between the delivery of the tubes by the rolls 3 and 4 to the conveyer belt and the discharge of these tubes to the bottoming mechanism, and hence the 20 paste of the seams in the tubes will have that much longer to dry and set.

At this point I may refer to the illustration in Fig. 5, in which 15 designates a tube corresponding to the tubes 12 and 13 in Fig. 1, from which illustration it will be seen that the paper or other material constituting the tube is folded over so that the edges overlap as indicated at 16 to provide a seam extending longitudinally of the tube, the overlapping edges of the paper, as will be understood, previously having been pasted. This figure illustrates the seam as opened at 17 due to manipulation of the tube in the bottoming mechanism, and it is the purpose of this invention to prevent this occurring. It will be understood, of course, that the seams of the tubes as the tubes are delivered from the rolls 3 and 4 have been perfectly formed.

40 A short distance from the receiving end of the conveyer belt 5, i. e., the end passing about the roller 6, I provide a positioning roller 18 mounted in suitable adjustable bearings 18^a and positioned just above the upper lead of the conveyer belt. As the tubes are deposited on the conveyer belt 5 by the rollers 3 and 4 this roller 18 which is adjustable according to length of tube will retard tube and position it properly on belt 5.

50 The tubes after passing beneath the roller 18 are carried by the conveyer belt about a large roller 11 during which time they are subjected to an appreciable pressure owing to the fact that they are gripped or squeezed between the belt and the roller in their passage about the roller, as will be obvious. As the tubes complete their travel about the roller 11 they are discharged upon a plate 19, being deposited upon this plate in inverted position with respect to the position they occupy in traveling to the roller 11. This plate 19 is immediately below the belt 5 as will be seen from Fig. 1, so that the tubes will be pushed along the plate until they are caused to enter 60 between the belt 5 and a pair of conveyer

belts 20 which are mounted on rollers 21, 22, 23 and 24, these rollers being so disposed that the belts are led about a portion of the periphery of the roller 10 and in close proximity to the belt 5. By this construction, therefore, the tubes are carried between the belts 20 and 5 around a portion of the periphery of the roller 10, being finally discharged at the point 25 from between the belts, their further or continued transfer being effected by the belt 5 only.

As will be seen from Fig. 1 and as will be obvious, the tubes which were again subjected to pressure, by the action of the belts 20 and 5 and the roller 10, will continue their travel toward the bottoming mechanism until they arrive beneath the adjustable presser roller 26 which lies immediately above the conveyer belt 5. The tubes are discharged from the conveyer belt 5, by the roller 26, between a positively driven roller 27 and driven sector rollers 28. The peripheral speed of the sector rollers 28 is such, when the tubes are being transferred in overlapping relation, as to accelerate the rate of travel of the leading or lowermost tube of the load with respect to the other tubes, so as to withdraw such tubes successively from beneath the following tubes and move the same along a plate 30 and between rollers 31 by which the tube is delivered upon a frame 32 along which the tubes are caused to pass to the bottoming mechanism, as will be presently described. A leading tube just being picked up by the sector rollers 28 has been designated 29. The rollers 28 are made in the form of sectors, so as to permit of the tubes passing into position properly between the rollers 28 and the roller 27 before being picked up. The roller 26 which is adjustable is adjusted so that when sector roller 28 picks up the leading tube shown as 29 the rear end of tube 29 has just passed under the center or grip of before mentioned roller 26, this prevents pulling ahead of following tubes until desired.

Positively driven sprocket chains 33 mounted on sprockets 34, 35 and 36 are provided, these chains being in such position that the leads 37 thereof travel parallel to and beneath the frame 32, as will be plainly seen from an inspection of Fig. 1. These chains travel in the direction of the arrow thereon and carry a series of fingers 38, these fingers projecting upwardly as will be seen from Fig. 1 between the sides of the frame, and so timed as to engage the rear end of the tubes as they are deposited upon the frame. A tube 39 is shown on the frame in Fig. 1 and an inspection of this figure will show that one pair of the fingers 38 will shortly engage this tube to move the same to the left, as viewed in Fig. 1, toward the bottoming mechanism.

As the tubes are moved positively along the frame 32 by the fingers 38 they are finally

pushed between rollers 40 and 41. The latter are in the form of sector rollers, as illustrated in Fig. 1. In fact these rollers are the same type of roller as the sector rollers 28 above referred to. As the tubes are moved successively between the rollers 40 and 41 it will be obvious that they will be gripped or pinched thereby to be withdrawn entirely from the frame 32 and passed into the bottoming mechanism (not shown). To prevent undesired or premature movement of the tubes from the frame 32 a stop 42 is provided adjacent the discharge end of the frame. This stop is attached to an arm 43 which is pivoted at 44 and carries a cam follower 45 cooperating with a cam 46 on the shaft 47 on which the rollers 41 are mounted. This cam is so positioned on the shaft 47 with respect to the positioning of the rollers 41 that the stop 42 will be lifted at the proper instant by the action of the cam 46 to permit of the passage of a tube between the rollers.

The main drive shaft for the mechanism above described is designated 48, this shaft, 25 being geared to a drive shaft 49 extending lengthwise of the machine and geared by worm and gear 50 to a shaft 51 extending transversely of the machine. This shaft 51 carries a gear 52 meshing with an intermediate gear 53 on an adjustable arm 54 on the shaft 55. This shaft 55 also extends transversely of the machine and carries the roller 11, which roller, as above pointed out, is one of the rollers carrying the conveyor belt 5. 35 The shaft 55 is provided with a gear 56 meshing with the intermediate gear 53. This gear 56 also drives a gear train composed of gears 57 and 58, the latter meshing with a gear 59 on the shaft 60 on which shaft is 40 mounted the roller 10. This mechanism, therefore, provides a positive drive for the rollers 10 and 11 and a drive for the conveyor belt 5 as well as the conveyor belts 20. In order that the speed of the conveyor belt 5 may 45 be adjusted without varying the speed of the main drive shaft 48 and hence without varying the speed at which the tubing and bottoming mechanisms are driven, the gear 52 may be substituted by another gear, larger or 50 smaller as the case may be depending upon whether the conveyor belt is to be speeded up or slowed down, and the adjustable arm 54 has been provided to permit of this substitution.

55 The sectors 28 are mounted on shaft 61 extending transversely of the machine and are driven from the gear 52A on the shaft 61. The gear 52A in turn is driven from a gear 63 on the shaft of the roller 27, this gear being driven from intermediate gear 64. The gear 64 receives its drive from gear 65 on the shaft 66, carrying the sprockets 35 driven by the chains 33. These chains, and hence the shaft 66, are driven by the sprockets 34 65 on the shaft 67 which is driven from the gear

68 through intermediate gear 69, driven by the gear 70 on the shaft 62. This shaft 62 receives its drive from the shaft 49 and the drive for the bottoming mechanism, not shown. The rollers 31 are geared together and driven by the intermediate gear 71 which is in mesh with the gear 65 on driven shaft 66.

70 From the foregoing, therefore, it will be seen that I have provided means intermediate the tube-forming mechanism and the bottoming mechanism in a bag forming machine for transferring tubes from the tube-forming mechanism to the bottoming mechanism in which the speed of the transfer mechanism can be adjusted as desired relatively to the speed of the tubing mechanism and bottoming mechanism so as to convey the tubes in overlapped position or in end to end position just as desired, but in any event to consume sufficient time in the transfer operation to enable the paste of the seams to dry and set sufficiently to prevent the seams opening during the bottoming operation. It will be seen also that my improved mechanism provides for subjecting the seams to pressure during their transfer which further aids in preventing accidental opening of the seams.

75 It is obvious that modifications may be made in the apparatus above described within the scope of my invention.

80 What I claim is:—

1. In a bag forming machine comprising tube-forming mechanism and bottoming mechanism, intermediate means for transferring tubes from the tube-forming mechanism to the bottoming mechanism, the speed of said transferring means being adjustable relatively to said mechanisms.

85 100 105 110 115 120 125 130

2. In a bag forming machine, means for transferring material from the tube-forming mechanism of the machine to the bottoming mechanism, and means for varying the speed of said mechanism relatively to the speed of the tube-forming and bottoming mechanisms.

3. In an automatic bag forming machine comprising tube-forming mechanism and bottoming mechanism, and conveyor mechanism intermediate the tube-forming mechanism and the bottoming mechanism for effecting a transfer of material from the former to the latter, the speed of said conveyor mechanism being adjustable relatively to the tube-forming and bottoming mechanisms to vary the relative positions in which the tubes are transferred.

4. In a bag forming machine comprising tube-forming mechanism and bottoming mechanism, intermediate mechanism for transferring tubes from the tube-forming mechanism to the bottoming mechanism, said intermediate mechanism effecting a positive progression of the tubes throughout a portion of their travel.

5. In a machine for forming bags the com-

bination of tube-forming and cutting-off mechanism, bottoming mechanism, and intermediate transferring mechanism for effecting a transfer of the tubes from the first mentioned mechanism to the second mentioned mechanism in overlapped relation throughout a portion of their travel.

6. In a machine for forming bags the combination of tube-forming and tube cutting-off mechanism, bottoming mechanism, and means for effecting a transfer of tubes from the tube-forming and cutting-off mechanism to the bottoming mechanism, said transferring mechanism effecting a transfer of the tubes in overlapped relation throughout the first portion of their travel, and means for effecting transfer of the tubes singly in the final portion of their travel.

7. In a machine for forming bags the combination of tube-forming and tube cutting-off mechanism, bottoming mechanism, intermediate transfer mechanism for effecting transfer of the tubes from the first mentioned mechanism to the second mentioned mechanism, the tubes being transferred throughout a portion of their travel at a rate differing from their rate of travel throughout the other portion of their travel.

8. In a machine for forming bags the combination of tube-cutting-off mechanism, bottoming mechanism, and transferring means for effecting transfer of tubes from the tube-cutting-off mechanism to the bottoming mechanism at variable speeds.

9. In a machine for forming bags the combination of tube-cutting-off mechanism, bottoming mechanism, means for effecting transfer of tubes from the tube-cutting-off mechanism to the bottoming mechanism, and means in the path of travel of the tubes being transferred for accelerating the tubes individually with respect to the following tubes.

10. In a machine for forming bags, tube-cutting-off mechanism transfer mechanism for transferring the cut off bag tubes from the cutting-off mechanism to the bottoming mechanism of the machine, and a roller cooperating with the tubes while their transfer is being effected, the peripheral speed of which is in excess of the linear speed at which the tubes are brought thereto.

11. In a machine for forming bags, the combination of tube cutting-off mechanism and bottoming mechanism, transfer mechanism for transferring bag tubes from the cutting-off mechanism toward the bottoming mechanism in overlapping relation, and a sector roller in the path of travel of the overlapped tubes for engaging the individual tubes singly to withdraw the lowermost tube from beneath the overlapping tubes.

12. In a machine for forming bags the combination of tube-forming and cutting-off mechanism, bottoming mechanism, intermediate means for transferring tubes from the

tube-forming mechanism and cutting-off mechanism to the bottoming mechanism, said means operating to effect during the transfer a reversal in the direction of travel of the tubes.

13. In a machine for forming bags the combination of tube-forming and cutting-off mechanism, bottoming mechanism, intermediate means for transferring tubes from the tube-forming and cutting-off mechanism, to the bottoming mechanism, and comprising a conveyer so disposed as to effect a reversal in the direction of travel of the tubes during their travel.

14. In a machine for forming bags the combination of tube-forming and cutting-off mechanism, bottoming mechanism, intermediate transfer means, said means comprising a conveyer belt, rollers about which the said belt is trained, said rollers and belt being so disposed relatively that throughout a portion of their travel the tubes being transferred are held between said belt and one of said rollers.

15. In a machine for forming bags the combination of tube-forming and cutting-off mechanism, bottoming mechanism means for transferring bag tubes from the tube-forming and cutting-off mechanism to the bottoming mechanism, and comprising a belt conveyer, and a pair of cooperating rollers, one of which is segmental, for receiving the tubes as they reach the end of the belt conveyer to effect further travel of the tubes toward the bottoming mechanism.

16. In a machine for forming bags and comprising tube-forming mechanism and bottoming mechanism, intermediate means for effecting transfer of tubes from the tube-forming mechanism to the bottoming mechanism, and comprising means adjacent the bottoming mechanism for positively advancing the tubes individually.

17. In a machine for forming bags, means for transferring bag tubes from the tube-forming portion of the machine to the bottoming mechanism, and comprising means adjacent the delivery end of the transfer mechanism for effecting individual and positive advance of the tubes, and stop mechanism cooperating with said positive advancing means and operating in timed relation therewith to prevent premature advance of the tubes.

18. In a machine for forming bags and comprising tube-forming mechanism and bottoming mechanism, intermediate means for effecting transfer of tubes from the tube-forming mechanism to the bottoming mechanism, and comprising positively driven fingers adjacent the bottoming mechanism for effecting individual and positive advance of the tubes toward the bottoming mechanism.

19. In a machine for forming bags and comprising tube-forming and bottoming

- mechanisms, intermediate means for effecting continuous transfer of bag tubes from the tube-forming mechanism toward the bottoming mechanism, a positively driven chain adjacent the bottoming mechanism positioned so that one lead thereof moves in the desired direction of travel of the tubes, and fingers carried by said chain for engaging the tubes successively to advance them toward the bottoming mechanism. 5
20. In a machine for forming bags and comprising tube-forming mechanism and bottoming mechanism, intermediate means for transferring tubes from the tube-forming mechanism to the bottoming mechanism and adjustable to transfer the tubes in spaced relation or in overlapped relation. 70
21. In a machine for forming paper bags and comprising tube-forming mechanism and bottoming mechanism, intermediate transfer mechanism comprising a conveyer, and an adjustable positioning roller cooperating therewith and mounted adjacent the delivery of the tube-forming mechanism. 75
22. In a machine for forming paper bags and comprising tube-forming mechanism and bottoming mechanism, means for transferring tubes from the former to the latter and comprising a belt, a sector roller for receiving tubes from said belt, and an adjustable roller mounted adjacent said sector roller and cooperating therewith to control the proper delivery of tubes successively from said belt. 80
23. In a machine for forming bags and comprising tube-forming mechanism and bottoming mechanism, a belt conveyer intermediate said mechanisms, a deflector adjacent the tube-forming mechanism for deflecting tubes being discharged from the tube-forming mechanism upon said belt conveyer, rollers about which said belt conveyer is trained, the tubes being conveyed by the belt being pressed throughout a portion of their travel between the belt and one of said rollers. 85
24. In a machine for forming bags the combination of tube-forming mechanism and bottoming mechanism and means intermediate said mechanism for pressing the seams of the tubes in the passage of the tubes to the bottoming mechanism, said pressing means comprising a belt and a roller about which the belt is trained, said belt carrying the tubes to be pressed between one face thereof and the face of said roller. 90
25. In a machine for forming bags and comprising tube-forming mechanism and bottoming mechanism, tube pressing means intermediate the tube-forming mechanism and the bottoming mechanism and comprising a belt conveyer, a deflector adjacent the tube-forming mechanism for deflecting the tubes being discharged therefrom upon the conveyer and an adjustable positioning roller co-operating with said deflector. 95
26. In a bag forming machine comprising tube forming mechanism and bottoming mechanism, means intermediate the tube-forming and bottoming mechanisms for transferring tubes from the former to the latter and to press the tubes while effecting their transfer, said intermediate mechanism comprising a belt conveyer, two rollers about which the conveyer passes, said conveyer and rolls being so disposed that tubes upon the conveyer are passed about one of said rollers between the conveyer and the face of said roller, and a second belt cooperating with said conveyer and disposed adjacent the second roller, the tubes after passing between the conveyer and the first roller, passing between the conveyer and said belt about the periphery of the second roller. 100
27. Bag forming mechanism comprising tube-forming mechanism and bottoming mechanism, pressing means intermediate said mechanisms and comprising two positively driven rollers travelling in opposite directions and a belt conveyer on which tubes leaving the tube-forming mechanism are deposited and carried by the said conveyer about said rollers, the tubes in passing about one of said rollers being carried between the conveyer and the periphery of the roller, a drive shaft for driving the tube-forming mechanism, geared to said rollers, and means for varying the speed of rotation of said rollers without varying the speed of said drive shaft thereby to vary the speed of the conveyer with respect to the tube-forming mechanism. 105
28. In a machine for forming bags and comprising tube-forming mechanism and bottoming mechanism, positively driven fingers adjacent the bottoming mechanism for effecting individual and positive advance of tubes formed in the tube-forming mechanism toward the bottoming mechanism and a cam controlled stop adjacent the bottoming mechanism for regulating the movement of the tubes into the bottoming mechanism. 110
29. In a machine for forming bags the combination of tube-forming mechanism and bottoming mechanism, positively driven fingers adjacent the bottoming mechanism for advancing tubes formed in the tube-forming mechanism into the bottoming mechanism, a stop adjacent the bottoming mechanism and a cam driven in timed relation to the bottoming mechanism for controlling said stop thereby to control the movement of the tubes into the bottoming mechanism. 115
30. In a machine for forming bags, the combination of tube cutting-off mechanism, bottoming mechanism, and means intermediate the tube cutting-off mechanism and the bottoming mechanism for pressing the seams of the tubes in their passage to the bottoming mechanism. 120
31. In a machine for forming bags, the combination of tube forming mechanism and 125

bottoming mechanism, and means intermediate the tube forming mechanism and the bottoming mechanism for transferring the tubes from the tube forming mechanism to the bottoming mechanism and for pressing the seams of the tubes while being transferred.

5 This specification signed this 1st day of March, 1928.

ADOLPH POTDEVIN.
